Attey.

UNITED STATES PATENT OFFICE.

FREDERICK H. MARTIN, OF AKRON, OHIO, ASSIGNOR TO THE B. F. GOODRICH COMPANY, OF NEW YORK, N. Y., A CORPORATION OF NEW YORK.

STOCKING PROTECTOR.

Application filed July 28, 1928. Serial No. 295,418.

This invention relates to stocking protectors or leggings and its chief objects are to provide neatness of appearance; ease of application and removal; a snug fit for legs of 5 different sizes; and lightness in conjunction with water-impermeability.

Of the accompanying drawings:

Fig. 1 is a perspective view of a legging or stocking protector embodying my invention 10 in its preferred form.

Fig. 2 is a perspective view of the same in place on the leg of a wearer.

Referring to the drawings, the stocking protector comprises a leg-enclosing member 15 or structure 10 of highly flexible and elastic water-proofed material such as rubberized stockinet, which preferably is rubberized on the outer face only so that the surface which is exposed to splashes of mud and water will 20 be easily cleaned while the inner surface is of a texture more suitable for contact with the stocking of the wearer.

The protector is preferably adapted to be 25 opened throughout its length at the front, for ease of application and removal, and its vertical margins defining the front opening are provided with suitable fastening means, preferably the respective series of jaw members 30 11, 11 of a known type of slide-fastener adapted for complete separation of the margins. Preferably a tongue or shield 12 is attached to one of the margins to protect the 35 stocking against injury by the fastener and to permit the easy running of the slide 13 of the fastener.

The protector preferably extends above the 40 calf of the leg and at its lower end extends only so far as to overlap a little way upon the overshoe of the wearer, which may be a slide-fastener overshoe 14 as shown, the protector forming a neat junction therewith, excluding soot or other soiling material from the overshoe and thus protecting the ankle portion as well as the leg portion of the stock- 45 ing.

For ornamentation and for neatness of appearance, and especially for holding the protector securely in place during use although 50 permitting it readily to be removed, bands 15, 16 of longitudinally-elastic webbing or the like are mounted in the manner of cuffs upon the upper and lower ends respectively of the leg-enclosing member 10, in position to conceal the upper and lower ends of the slide-

fastener preferably by means of stitching of 55 a character such as to permit elongation and contraction of the webbing and the margin of the member 10 to which it is attached.

The type of stitching here shown, which is 60 well known in other associations as Merrow stitching, has been found to be particularly serviceable in providing a strong and at the same time elastic seam.

Each of the bands of webbing, 15, 16, is 65 provided with mating snap-fastener members, 17, 18, for joining its ends to secure the protector in place with the bands under suitable tension, and the stitching preferably is applied to the band only from a position a little short of each end portion of the band, 70 so that the end portions of the bands may be easily manipulated for joining and disjoining the snap-fasteners and so that the slide 13 of the slide-fastener may readily be concealed under the band at the top of its range 75 of movement. The stitching preferably is continued about the free ends of the elastic webbing to prevent fraying and for neatness.

In the process of manufacture the webbing 80 may be held in a slightly stretched condition while it is being sewed to the leg-enclosing member 10, so that the latter will be slightly puckered by the webbing when the latter is released, the resulting structure being one in which the cuff of webbing will have a high 85 range of extensibility, for fitting legs or ankles of different sizes, even though the member 10 to which it is stitched is less elastic than the webbing.

The member 10 may be first vulcanized and 90 then provided with the webbing members, so that the latter may be made in various colors and with elasticity and durability in high degree.

My invention is susceptible of modification 95 within its scope without sacrifice of all of the advantages set out in the above statement of objects, and I do not wholly limit my claims to the specific structure shown.

I claim:

1. A stocking protector comprising a highly flexible leg-encircling member terminating at the ankle at its lower end and formed with completely separable vertical margins, means on said margins for joining them, and additional, elastic leg-encircling means for constricting the leg-encircling member about the ankle of the wearer.

2. A stocking protector comprising a leg-encircling member terminating at the ankle at its lower end and formed with completely separable vertical margins, and a completely separable slide-fastener for joining said margins. 30
3. A stocking protector comprising a leg-encircling member terminating at the ankle at its lower end and formed with completely separable vertical margins, a completely separable slide-fastener for joining said margins, and a constricting cuff mounted upon an end margin of said member. 10
4. A stocking protector comprising a leg-encircling member terminating at the ankle at its lower end and formed with completely separable vertical margins, a completely separable slide-fastener for joining said margins, and a constricting cuff mounted upon an end margin of said member, the said cuff having separable end portions positioned to overlie an end of the slide-fastener. 20
5. A stocking protector comprising a leg-encircling member terminating at the ankle at its lower end and formed with completely separable vertical margins, a completely separable slide-fastener for joining said margins, and constricting cuffs mounted upon the respective end margins of said member, each 25
- cuff having end portions positioned to overlie an end of the slide-fastener. 30
6. A stocking protector comprising a highly flexible leg-encircling member terminating at the ankle at its lower end and formed with completely separable vertical margins, 35 means on said margins for joining them, and additional, elastic leg-encircling means for constricting the leg-encircling member about the ankle of the wearer, the said constricting means comprising a circumferentially elastic cuff joined to the said member in an elastic seam. 40
7. A stocking protector comprising a highly flexible leg-encircling member terminating at the ankle at its lower end and formed with completely separable vertical margins, 45 means on said margins for joining them, additional elastic leg-encircling means for constricting the leg-encircling member about the ankle of the wearer, the said constricting means comprising a circumferentially elastic cuff joined to the said member in an elastic seam and having free end portions, and means for detachably securing together the 50 said free end portions. 55

In witness whereof I have hereunto set my hand this 19th day of July, 1928.

FREDERICK H. MARTIN.
